E. K. BOTTLE,
MANIFOLDING SALESBOOK,
APPLICATION FILED DEC. 8, 1920.

1,405,748.

Patented Feb. 7, 1922.

UNITED STATES PATENT OFFICE.

EDWARD KIRBY BOTTLE, OF ELMIRA, NEW YORK, ASSIGNOR TO AMERICAN SALES BOOK COMPANY, LIMITED, OF TORONTO, ONTARIO, CANADA, A CORPORATION OF ONTARIO, CANADA.

MANIFOLDING SALES BOOK.

1,405,748.

Specification of Letters Patent. Patented Feb. 7, 1922.

Application filed December 8, 1920. Serial No. 429,063.

To all whom it may concern:

Be it known that I, EDWARD K. BOTTLE, a citizen of the United States, residing at town of Elmira, in the county of Chemung 5 and State of New York, have invented certain new and useful Improvements in Manifolding Sales Books, of which the following is a full, clear, and exact description, such as will enable others skilled in the art to 10 which it appertains to make and use the same.

This invention relates to manifolding devices, and with respect to its more specific features, to manifolding sales books.

15 One of the objects of the invention is the provision of a practical sales book of such construction that its capabilities of use are increased and a close check kept upon the sales slips.

20 Another object of the invention is the provision of a practical sales book involving a tissue intersheet, which latter is not so apt to be accidentally separated from the book, nor torn.

25 Other objects will be in part obvious and in part pointed out hereinafter.

The invention accordingly consists in the features of construction, combinations of elements and arrangement of parts which 30 will be exemplified in the construction hereinafter set forth, and the scope of the application of which will be indicated in the following claims.

In the accompanying drawing forming 35 part of this specification, wherein similar reference characters refer to similar parts throughout the several views,

Figure 1 is a perspective view of a manifolding sales pad embodying the invention; 40 Fig. 2 is a diagrammatic view illustrating the pad and the arrangement and construction of the individual sheets;

Fig. 3 is a perspective view of a modified form of individual sheet; and

45 Fig. 4 is a perspective detail of the outer end of the form shown in Fig. 3, the fold being exaggerated.

Referring now more specifically to the drawing, the numeral 1 indicates a pad made 50 up of sheets or leaves the association of which is more clearly illustrated in Fig. 2. The numeral 2 indicates an original sheet of opaque paper, and 3 is a second or duplicate sheet of similar paper, these two sheets being 55 integral, in the embodiment illustrated in

Fig. 2, and folded along the line 30 which is a weakened line. The sheets 2 and 3 form a pair of superposed sheets, and whereas they are formed from an integral piece, folded at 30 as indicated, they may be 60 formed separate and joined along the line 30. The numeral 4 indicates a third sheet which, in the embodiment illustrated in Fig. 2, is a translucent sheet, as a tissue sheet. This sheet 4 lies between the sheets 2 and 3 65 when the latter are in superposed relation, and is adhesively connected to one of these sheets at a plurality of lines spaced apart longitudinally of the sheet so as to form a multiple-ply sheet. In the embodiment 70 illustrated in Fig. 2 the tissue sheet 4 is adhesively connected to the original sheet 2 at the end 5 of the original sheet where a portion of the area of the two sheets is pasted together by a suitable adhesive indicated by the oblique lines in the drawing. Similarly the sheets 2 and 4 are pasted together along a plurality of areas indicated at 6 and 7 intermediate the ends of the original sheet 2. Between the adhesively connected areas of the original sheet 2 and the tissue sheet 4, these two sheets are unconnected, so that when the adhesively joined parts are separated or torn from each other, complete separation of the sheets 2 and 4 is 80 effected.

The duplicate sheet 3 is enough longer than the original sheet 2 to form an extended portion 8 adapted with other similar sheets 3 and attached sheets 2 to be bound 90 in a pad, as by means of staples 9. The numeral 10 indicates a sheet of double-faced transfer or carbon paper which may be bound with the pad by means of the staples 9, and lies between the duplicate sheet 3 and 95 the tissue sheet 4, the outer end 11 of the carbon sheet 10 being free so that as the transcribed sheets are torn from the book the carbon will be retained in the book and rest upon the under sheets ready to be placed 100 in manifolding relation.

Along one of the transverse margins of the adhering areas 6 and 7 the original sheet 2 and the tissue sheet 4 are provided with weakened lines as indicated at 12 and 13 in 105 the present embodiment.

In operation the original sheet 2 with its adhering intersheet 4 is drawn back into the position illustrated, for instance, in Fig. 1, which will permit the carbon sheet 10 to fall 110

on the uppermost duplicate sheet 3. Thereupon the sheets 2 and 4 are folded down onto the carbon and the desired inscriptions may be made on the original sheet. These inscriptions will be duplicated upon the underlying sheet 3 and also upon the under face of the tissue sheet 4. Thereupon the sheet 3 may be torn from the pad along the weakened line 14 and may be separated from the sheets 2 and 4 by tearing along the weakened line 30. Also the multiple-ply record section included by the original sheet 2 and tissue sheet 4 may be divided along the weakened lines 12 and 13, thus providing, in the embodiment illustrated, three multiple-ply record sections, each including an original record on the opaque sheet section 2 and a duplicate record on the tissue sheet section 4.

By connecting the intersheet 4 to the original sheet at a plurality of points spaced apart from each other as explained, the intersheet is effectively maintained in registry at all times with the original sheet so that any printed forms thereon take their proper place relative to each other. Furthermore, by attaching these two sheets together at a plurality of areas, and especially when the areas of attachment occur near the ends of the two sheets, the two sheets may be manipulated practically as a single sheet with but a minimum chance of the intersheet being torn. This is especially desirable when the intersheet is a tissue sheet and consequently more readily torn. The provision of the multiple-ply sheet sections finds especial utility in many situations. In systems of keeping accounts involving the operation of manifold sales books, various memoranda are made in duplicate, but are intended to be torn from the book in connected condition, forwarded to the office, and subsequently the duplicate sections torn apart. The present embodiment provides for the making of such duplicate memoranda and permits the transportation of the sheets in attached condition with assurance that they will not be separated until separation is subsequently purposely effected.

In the above description reference has been made particularly to the sheets 2 and 3 with the intersheet 4 attached. It is to be understood that the pad 1 is composed of a series of such sheets in superposed relation and bound together as illustrated.

In some instances, as when a tissue intersheet is not desired, the intersheet may be of the same material as the opaque record sheets 2 and 3. Under such circumstances a convenient way of providing the intersheet is illustrated in Fig. 3, where the intersheet is shown at 15, the same being an integral extension or leaf of the sheet 2 folded and weakened along the line indicated at 16, and pasted to the underside of the sheet 2 at the areas indicated at 17 and 18,

the inner end of the intersheet being free as indicated at 19. Like the sheets 2 and 4, the margins of the pasted areas 17 and 18 are provided with weakened lines as indicated at 20 and 21 for the more ready division of the multiple ply sheet into multiple 70
ply sections.

Thus by the above described construction are accomplished, among others, the objects hereinbefore referred to. 75

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense. 80

It is also to be understood that the language used in the following claims is intended to cover all of the generic and specific features of the invention herein described, and all statements of the scope of the invention which, as a matter of language, might 90 be said to fall therebetween.

Having described my invention, what I claim as new and desire to secure by Letters Patent, is:—

1. A manifolding sales book including, in 95 combination, a pair of superposed sheets adhesively connected together at a plurality of areas spaced apart longitudinally of the sheets, said sheets being unconnected between adjacent areas.

2. A manifolding sales book including, in combination, a pair of superposed sheets adhesively connected together at a plurality of areas spaced apart longitudinally of the sheets, said sheets being unconnected between 105 adjacent areas, said sheets having weakened lines along one of the transverse margins of one or more of said adhering areas.

3. A manifolding sales book including, in combination, a pair of superposed sheets adhesively connected together at a plurality of areas spaced apart longitudinally of the sheets, said sheets being unconnected between adjacent areas, one of said sheets having a weakened line along one of the transverse 115 margins of one or more of said adhering areas.

4. A manifolding sales book including, in combination, a pair of superposed sheets adhesively connected together at a plurality of 120 areas spaced apart longitudinally of the sheets, said sheets being unconnected between adjacent areas, one of said sheets being a tissue sheet.

5. A manifolding sales book including, in 125 combination, a pair of superposed sheets adhesively connected together at a plurality of areas spaced apart longitudinally of the sheets, said sheets being unconnected between adjacent areas, said sheets having weakened 130

- lines along one of the transverse margins of one or more of said adhering areas, one of said sheets being a tissue sheet.
6. A manifolding sales book including, in combination, a pair of superposed sheets adhesively connected together at a plurality of areas spaced apart longitudinally of the sheets, said sheets being unconnected between adjacent areas, one of said sheets having a weakened line along one of the transverse margins of one or more of said adhering areas, one of said sheets being a tissue sheet.
7. A manifolding sales book including, in combination, a pair of superposed sheets adhesively connected together at at least two separate areas spaced apart, thereby providing at least two multiple-ply record sections.
8. A manifolding sales book including, in combination, a pair of superposed sheets adhesively connected together at at least two separate areas spaced apart, thereby providing at least two multiple-ply record sections, one of said sheets being translucent.
9. A manifolding sales book including, in combination, a pair of superposed sheets connected together along a plurality of lines spaced apart longitudinally of the sheets, one of said lines of connection including adhesively connected areas intermediate the ends of one sheet.
10. A manifolding sales book including, in combination, a folded sheet providing relatively superposed leaves, two of said leaves being adhesively connected together along an area spaced from the fold of the sheet.
11. In testimony whereof I affix my signature, in the presence of two witnesses.
- EDWARD KIRBY BOTTLE.
